Des. 216,051
Patented Nov. 18, 1969

216,051

PORTABLE RADIO CABINET

Melvin H. Boldt, Glenview, Ill., assignor to Zenith Radio Corporation, Chicago, Ill., a corporation of Delaware

Filed Oct. 29, 1968, Ser. No. 14,213

Term of patent 14 years

Int. Cl. D14—03

U.S. Cl. D56—4

FIG. 1

FIG. 2

FIG. 3

← 5.

FIG. 5

FIG. 4

FIGURE 1 is a front perspective view which depicts the front, top and right side of my design for a portable radio cabinet;

FIGURE 2 is a rear perspective view showing the back, top and left side of my design;

FIGURE 3 is a front elevational view thereof;

FIGURE 4 is a bottom view; and

FIGURE 5 is a right side elevational view of my design, partially in section as seen from line 5-5 of FIGURE 3.

Portions of the drawing are stippled to indicate contrast in appearance.

I claim:

The ornamental design for a portable radio cabinet, as shown and described.
